UNITED STATES PATENT OFFICE.

MARK C. STOVER, OF DECATUR, ILLINOIS.

WINDOW-CATCH.

1,065,743.

Specification of Letters Patent. Patented June 24, 1913.

Application filed July 16, 1912. Serial No. 709,738.

To all whom it may concern:

Be it known that I, MARK C. STOVER, a citizen of the United States, residing at Decatur, in the county of Macon and State of Illinois, have invented new and useful Improvements in Window-Catches, of which the following is a specification.

This invention relates to window catches, the object in view being to provide a safety catch for arresting the downward descent of the window sash upon breakage of one or both of the sash cords thereof, thereby avoiding the breakage of the pane or panes of glass carried by the sash.

15 A further object of the invention is to provide means for fastening the catch in an inoperative position when not needed in use.

With the above and other objects in view, the invention consists in the construction, 20 combination and arrangement of parts, as will be hereinafter more fully described, illustrated in the accompanying drawings, and pointed out in the claims hereunto appended.

25 In the drawings: Figure 1 is a vertical longitudinal section through the casing of the window catch, showing the operative parts thereof in elevation. Fig. 2 is a similar view, showing the operation of the wedge 30 in throwing the catch into action. Fig. 3 is a side elevation of the casing complete. Fig. 4 is a face or edge view of the casing, showing the jamb engaging teeth on the catch. Fig. 5 is a side elevation of the face plate, 35 showing the wedge releasing and fastening button. Fig. 6 is a reduced elevation of a portion of a window sash, showing the catch of this invention applied thereto. Fig. 7 is a detail view of the thumb screw.

40 The sash catch contemplated in this invention comprises essentially a substantially rectangular casing 1, provided at its front edge with upwardly and downwardly extending flanges 2 and 3, adapted to receive 45 screws, whereby the casing as a whole may be secured to one of the sides of the window sash, in the same manner as an ordinary mortise lock, as indicated in Figs. 1, 2 and 6.

Within the casing 1 is mounted a pivoted 50 catch 4, the same being pivotally mounted adjacent to its upper end, as shown at 5, while at its lower end it is provided with an outwardly projecting portion or arm 6 adapted to move through an opening 7 in 55 the casing, and provided with sharp pointed teeth 8, which extend outwardly and down-

wardly, so as to insure the same becoming firmly embedded in the jamb of the window frame, when the catch is thrown outward by means hereinafter described.

60 Behind the catch 4 and within the casing 1 is mounted a sliding wedge 9 which bears against the rear wall 10 of the casing and also against the rear edge of the catch 4. Connected to the upper part of the wedge 9 is a plunger 11 which operates through an opening in the top of the casing, and has its lower end preferably threaded into an internally threaded pocket in the wedge, as shown at 12. The plunger 11 is also provided with a hinged joint 13 at a suitable point thereof, so as to allow of the relative pivotal movement between the wedge and the plunger, as the plunger and wedge are moved downward.

65 Extending upward from the top wall 14 of the casing is a small spring housing 15, in which is arranged a coiled expansion spring 16, the upper end of which is held in the housing, while the lower end thereof 70 engages a shoulder on the plunger, or said spring may rest against the upper edge of the wedge 9. The force of this spring is utilized to thrust the wedge 9 downward, when the plunger is released.

75 At its upper end, the plunger 11 is provided with an eye 17 adapting the usual sash cord or chain 18 to be connected thereto, the idea being that when such sash cord or chain breaks, the plunger is released and thrown 80 downward by the spring 16, which also throws the wedge 9 downward and forces the engaging teeth of the catch 4 outward into firm engagement with the window jamb. This prevents the sash from falling and 85 breaking the glass carried thereby.

90 In order to provide for restoring the wedge to its inoperative position, a thumb piece or button 19 is provided, the same having its shank threaded, as shown at 20, and 95 screwed into a threaded socket 21 in the wedge. A slot 22 is formed in the adjacent side wall of the casing 1 to admit of the movement of the shank of the thumb piece, and an escutcheon or face plate 23 is also secured to the inner face of the sash to give 100 the same an ornamental appearance, said face plate being also provided with a slot 24, through which the shank of the thumb piece passes, and along which it operates 105 in the up and down movements of the wedge.

110 It will be understood that the catch is held

inoperative as long as the sash cords remain intact. As soon as a sash cord breaks, however, the safety catch is thrown out into engagement with the jamb, and thereby 5 quickly arrests the sash and prevents further downward movement thereof. To release the sash from its position, it is only necessary to push upward on the thumb piece described, thereby drawing the teeth of the 10 catch out of engagement with the jamb. A new sash cord may then be put into position and attached to the plunger of the catch.

What is claimed is:

- 15 1. A window catch for sashes, comprising a casing, a pivoted catch therein adapted to be projected through an opening in the casing and provided with jamb engaging teeth, a spring thrust wedge operating be- 20 tween the catch and a wall of said casing to press the catch into action, and a sash cord sustained plunger connected with said wedge and adapted to be released upon the break- age of the sash cord.
- 25 2. A window catch for sashes, comprising a casing, a pivoted catch therein adapted to be projected through an opening in the casing and provided with jamb engaging teeth, a spring thrust wedge operating be- 30 tween the catch and a wall of said casing to

press the catch into action, and a sash cord sustained plunger connected with said wedge by a hinge joint and adapted to be released upon the breakage of the sash cord.

3. A window catch for sashes, comprising 35 a casing, a pivoted catch therein adapted to be projected through an opening in the casing and provided with jamb engaging teeth, a spring thrust wedge for pressing the catch into action, a sash cord sustained 40 plunger connected with said wedge and adapted to be released upon the breakage of the sash cord, and a thumb piece for re- tracting said wedge.

4. A window catch for sashes, comprising 45 a casing, a pivoted catch therein adapted to be projected through an opening in the cas- ing and provided with jamb engaging teeth, a spring thrust wedge for pressing the catch into action, a sash cord sustained plunger 50 connected with said wedge and adapted to be released upon the breakage of the sash cord, and a thumb screw for retracting and fas- tening said wedge.

In testimony whereof I affix my signature 55 in presence of two witnesses.

MARK C. STOVER.
